CLARENCE E. TIBBS, OF SEATTLE, WASHINGTON, ASSIGNOR OF ONE-THIRD TO
B. B. NERVO, OF SEATTLE, WASHINGTON.

MIRROR-HOLDER.

1,267,933.

Specification of Letters Patent.

Patented May 28, 1918.

Application filed June 26, 1917. Serial No. 177,080.

To all whom it may concern:

Be it known that I, CLARENCE E. TIBBS, a citizen of the United States, residing at Seattle, in the county of King and State of Washington, have invented new and useful Improvements in Mirror-Holders, of which the following is a specification.

This invention relates to a holder for mirrors of the type found in ladies' hand bags, or upon the dressing tables in hotels and the like, for the use of ladies in dressing their hair and other purposes of a similar character.

Many persons, especially women, have found it difficult to satisfactorily use these mirrors in making their toilet, as to obtain a satisfactory view of the head, necessitates holding the mirror in one hand, which interferes with the use of both hands while dressing the hair.

It is my principal object to overcome this difficulty by providing a simple and inexpensive support for these mirrors which may be carried in a hand bag if found desirable and either temporarily, or permanently connected with a support such as a chair back or the like, without detracting from its appearance, or interfering with the use thereof.

Another object of the invention is to provide a holder for mirrors of this character which though capable of being attached to a support in various positions comprises few parts which may be accomplished by means of the block in the back of which is formed a pair of recesses, the uppermost of which may be employed as a socket for the mirror handle by partially closing an open side thereof with the fixed jaw of a spring actuated clasp mounted upon the block and by means of which, the block may be attached to a support.

A further object of the invention is to provide the block with an attaching clasp, the fixed jaw of which has extending upwardly therefrom above the uppermost recess in the block, an arm which serves as a brace for the mirror when the handle thereof is inserted in the recess.

A still further object of the invention is to so shape the block that when applied to the back of a chair, the block will cause no discomfort to a person occupying the chair and will also permit securing elements to be passed through openings therein for permanently attaching the block to a support with-

out likelihood of the securing elements splitting the block should an unusual strain be imposed upon the block.

With these and other objects in view, the invention resides in the novel combination and arrangement of parts, which will be hereinafter described and particularly pointed out in the claim.

The preferred embodiment of the invention has been illustrated in the accompanying drawing, although no restriction is necessarily made to the precise details of construction therein shown, as changes, alterations, and modifications within the scope of the claim may be resorted to when desired.

In the drawing:

Figure 1 is a perspective view of a mirror holder constructed in accordance with the invention.

Fig. 2 is a plan view of the back thereof.

Fig. 3 is a vertical longitudinal section through the holder showing the same mounted upon a support and holding a mirror.

Fig. 4 is a horizontal transverse sectional view through Fig. 1.

Fig. 5 is a vertical transverse sectional view through the holder, showing the same permanently secured to a support.

Like characters of reference denote corresponding parts throughout the several views in the drawing.

Referring now to the drawing in detail, the letter A designates a support which in this instance has been shown as the upper rail of a chair back and upon which is mounted the improved mirror holder B having mounted therein a mirror C of the type commonly found upon dressing tables and the like.

The mirror holder B includes a block 5 of any material which may be suitably ornamented, although I prefer to employ wood, as such material can be stained and polished to correspond to the finish of furniture in common use. The block 5 is provided upon one side of its transverse center line with three beveled faces 6, 7, and 8 which, when the block is secured to a support, such as a chair, in a manner hereinafter described, prevent the block from causing discomfort to a person occupying the chair. The upper edge of the block 5 is beveled upon three sides as shown at 9 and has formed in its back 10 a longitudinally extending recess 11, 110

the bottom wall 12 of which is curved as shown, said recess opening out through the top of the block. Formed in the back 10 of the block below the recess 11 is a second recess 13 in which may be arranged advertising matter if found desirable, or a mirror of circular shape carried therein.

The spring actuated clasp 14, for connecting the block to a support, comprises a fixed jaw 15 which is secured to the back of the block 10 in any suitable manner to permit the jaw to partially close the open side of the recess 11 therein, so that the fixed jaw of the clasp may coact with the walls of the recess in retaining the handle of the mirror C in an upright position when inserted within the recess 11 of the block. Hingedly connected with the fixed jaw 15 is a movable jaw 20 between which and the fixed jaw may be arranged the outer rail of the chair back when the block is attached thereto by means of the clasp. To permit the support to be arranged between the jaws of the clasp, each jaw is provided with an arm 21, the arm 21 of the fixed jaw extends above the top of the block 5 to serve as a brace for the handle of the mirror C.

The block 5 has formed therein upon opposite sides of the recess 11, openings 22 through which may be passed the shanks of securing elements, such as screws, or the like, when the holder is permanently connected with a support.

In order that the mirror may be held by the holder at the proper angle when the holder is permanently connected with a support, I provide a tapered plate 23 which may

be interposed between the holder and the support either at the top or at the bottom of the holder as the occasion requires.

When it is desired to employ the holder as a support for a mirror, or the like, the block is attached to a support by means of the clasp 14 in the desired position and the handle of the mirror inserted in the socket in the block formed by the recess 11 and the fixed jaw of the clasp 14, it, of course, being understood that a suitable lining may be provided for the recess to prevent the marring of the handle of the mirror if found desirable.

From the foregoing description, taken in connection with the accompanying drawing, it is at once apparent that a mirror holder has been provided in which the parts comprising the same have been utilized to their fullest extent to decrease the cost of manufacture and to provide a mirror holder which will be highly efficient for the purpose set forth.

Having thus described the invention, what is claimed as new, is:

In a device of the class described, a block having a recess in one side thereof opening out through the top of said block, a reinforcing plate on said block coacting with said recess in providing the block with a handle receiving opening, attaching means on said plate, and an arm on said plate extending above the top of said block adapted to act as a brace for a handle inserted in the handle receiving opening in the block.

In testimony whereof I affix my signature.
CLARENCE E. TIBBS.
